TOY GUN

Edwin E. Foster, % Majik-Ironers, Inc., 402 Capital
National Bank Bldg., Austin, Tex.
Filed May 25, 1959, Ser. No. 815,342
4 Claims. (Cl. 124—11)

This invention relates to toy guns and more particularly to one piece molded hand guns or pistols for firing projectiles in the nature of hollow plastic balls.

A number of different types of toy guns have been proposed for shooting hollow plastic balls with a popping noise. One of the problems in connection with such guns has been in constructing the same so that they can be loaded and fired easily to adapt them for use by small children. This problem is particularly pronounced in the case of hand guns or pistols wherein firing is accomplished by compressing a hollow handle formed of resilient material.

It is one of the objects of the present invention to provide a toy gun which is formed of a hollow body of resilient material, such as rubber or plastic, and which can easily be loaded and fired even by small children.

According to a feature of the invention, the gun is provided with a hollow handle portion of resilient material adapted to be squeezed and compressed for firing the gun and which is formed with a strengthened rib extending along the forward wall thereof to be engaged by the fingers of a hand gripping the handle portion and pressed to compress the handle portion.

A further object is to provide a toy gun in which a ball or similar projectile is wedgedly sealed in a conically tapered muzzle end on the hollow barrel portion.

With this construction, the ball or similar projectile can easily be loaded simply by pressing it into the muzzle end and the amount of pressure required to discharge the ball can be varied in accordance with the wedging pressure exerted thereon in loading so that the gun can be used even by very small children.

Still another object is to provide a toy gun which is usable either to fire projectiles, such as balls, or as a water gun to eject streams of water.

The above and other objects and features of the invention will be more readily apparent from the following description when read in connection with the accompanying drawings, in which:

FIGURE 1 is an end elevation of a toy gun embodying the invention;

FIGURE 2 is a section on the line 2—2 of FIGURE 1;

FIGURES 3 and 4 are sections on the line 3—3 of FIGURE 2 showing the handle portion in relaxed and compressed condition, respectively;

FIGURE 5 is an end elevation of an alternative form of gun;

FIGURE 6 is a section on the line 6—6 of FIGURE 5; and

FIGURE 7 is a partial section similar to FIGURE 6 of still another alternative construction.

The gun, as shown in FIGURES 1 to 4, comprises a one piece molded body formed of resilient material, such as rubber or a relatively soft vinyl plastic, or the like. The body is formed with a cylindrical barrel portion 10 of a size loosely to receive two or more balls 11 which are preferably hollow, relatively light balls made of plastic, generally similar to conventional "ping-pong" balls. The balls 11 may be relatively soft so that they will deform relatively easily, but are resilient so that they will return to their spherical conditions when the pressure thereon is released. The barrel portion is of a diameter loosely to receive the balls through the major part of its length, but is formed adjacent to its muzzle or dis-

2

charge end with an annular restriction 12 slightly smaller in diameter than the balls to seal against the ball engaging it.

The barrel portion is integrally molded with a hollow handle portion 13 having relatively thin walls at its sides and back and reinforced at its forward wall by an integrally molded rib 14. The rib 14 may be serrated, as shown, to receive the fingers of a hand gripping the handle portion and preferably extends along the full length of the handle portion, as shown.

At the rear wall of the handle portion on the interior thereof a pin 15 is integrally molded in the gun body and is of a size to receive relatively closely the small diameter end of a spiral compression spring 16. In its expanded condition, the spring 16 will expand approximately to the restriction 12 and when balls 11 are loaded into the barrel portion 10, as shown in FIGURE 2, the spring will be compressed to urge the outermost ball with relatively light pressure into sealing engagement with the restriction 12.

To use the gun, the balls 11, in any desired number, according to the gun design, are forced into the barrel portion against the spring 16, as shown in FIGURE 2. Due to compressibility of the balls themselves and to the resilience of the material from which the gun is formed the balls can be forced past the restriction 12 relatively easily. This may be done by pressing the balls with the fingers or by pushing the muzzle of the gun over a ball resting on the floor, or a similar surface.

With the balls loaded, the handle portion may be gripped in the hand with the fingers of the hand overlying and engaging the rib 14. When the hand is closed, the handle portion will be compressed substantially as shown in FIGURE 4 with the rib 14 moving toward the back wall of the handle portion to compress the air in the hollow gun body. When sufficient pressure is created, which is of a relatively low order, the outermost ball 11 will be forced past the restriction 12 and will be discharged from the gun to the accompaniment of a popping noise. When the handle is released, it will return to its expanded condition, as shown in FIGURE 3, and will draw air in past the outermost ball so that the gun is again ready to fire. This operation may be continued until all of the balls in the barrel portion have been discharged.

FIGURES 5 and 6 illustrate an alternative construction which is also molded of one piece rubber or plastic with a hollow barrel portion 17 and a hollow handle portion 18 provided with a strengthened rib 19 similar to the rib 14 of FIGURES 1 to 4. In this construction, a single ball is intended to be fired at one time and the muzzle of the barrel portion is formed with a conical inward taper 21 slightly larger at its outer end than the diameter of a ball 22 and slightly smaller at its inner end than the ball diameter. In using this gun, to fire balls, a ball may be wedged into the conical tapered portion 21, as shown in FIGURE 6. One advantage of the construction is that the ball may be wedged in with different degrees of force to seal itself against the conical tapered portion so the more or less air pressure will be required to eject the ball. By this means a relatively small child who would not be able to force the ball in extremely tightly will be able to exert enough pressure on the handle portion to fire the ball while larger, stronger children may wedge the ball in more tightly to fire it with greater force through a greater distance and with a greater popping noise.

The gun, as shown in FIGURES 5 and 6, may be used alternatively as a ball firing gun or as a water pistol. For this purpose, the barrel portion inward of the position of the ball is formed with an annular groove 23 in which a disc 24 may be seated. The disc 24 is preferably molded of rubber or plastic material and is formed

near its center with a socket 25 to receive a tube 26 and with a relatively small orifice or nozzle 27 facing outwardly of the barrel portion. The tube 26 is of a length to extend into and near to the bottom of the handle portion, as shown.

The gun may be used to fire balls in the manner described above with the partition and tube in place and in this case the partition serves to limit the size of the firing chamber so that a sharper pop will result when the ball is fired. For use as a water pistol, the handle portion may be filled with water to any desired extent and when it is squeezed a stream of water will be ejected through the tube and the nozzle 27. Upon release of the handle after firing one shot of water, air will be drawn into the handle portion so that subsequent shots of water can be discharged until the water supply in the handle is exhausted. In use of the gun for this purpose, a large number of shots of water can be fired successively.

FIGURE 7 illustrates a further alternative construction which is generally similar to FIGURES 5 and 6 and in which corresponding parts are indicated by the same reference numerals. In this construction, an annular disc 28, which may be formed of hard rubber or plastic, is fitted into the groove 23 instead of the disc 24. The opening through the center of the annular disc 28 is provided with a noise maker, such as a reed 29, which is operable when air is being drawn into the gun body and handle portion to produce a whistling or rattling noise. By properly tuning the reed, it may be caused to produce a whistling or whining noise, similar to that made by a ricocheting bullet so that the popping noise accompanying ejection of the ball 22 will be followed by a whistle or whine suggestive of the noise produced by a ricocheting bullet.

While several embodiments of the invention have been shown and described herein, it will be understood that they are illustrative only and not to be taken as a definition of the scope of the invention, reference being had for this purpose to the appended claims.

What is claimed is:

1. A toy gun comprising a hollow body of resilient material defining a tubular barrel portion and a hollow handle portion at an angle to the barrel portion to be gripped in the hand of a user and compressed, the barrel portion being formed adjacent to its open end to seal against a ball which will be ejected by compressed air

when the handle portion is compressed, the walls of the handle portion being relatively thin and flexible, and a relatively thick and stiff strengthening rib extending along and coextensive in length with the forward wall of the handle portion to be engaged by the fingers of a hand gripping the handle portion and pressed to compress the handle portion, the strengthening rib remaining substantially straight and moving between the sides of the handle portion when the handle portion is compressed.

5 10 15 20 25 30

2. The toy gun of claim 1 in which the rib is integrally molded with the handle portion and projects beyond the forward wall of the handle portion to be engaged by the fingers.

3. A toy gun comprising a hollow body of resilient material defining a tubular barrel portion and a hollow handle portion at an angle to the barrel portion to be gripped in the hand of a user and compressed, the barrel portion being formed adjacent to its discharge end to seal against a ball which will be ejected by compressed air when the handle portion is compressed, a transverse partition in the barrel portion inwardly of the discharge end thereof and inwardly of the position occupied by a ball sealed in the barrel portion and formed with an opening therethrough, and a tube communicating with the opening and extending into the handle portion, the tube terminating in a nozzle at the opening in the partition providing for ejection of liquid from the handle.

4. The toy gun of claim 1 in which the barrel portion is formed adjacent its open end with a smooth continuous inward taper to receive and wedge against a ball so that the ball will be ejected by compressed air when the handle portion is compressed.
